UNITED STATES PATENT OFFICE

LEE D. JALKUT, OF LAWRENCE, NEW YORK, ASSIGNOR TO INGRAM RICHARDSON CORPORATION, OF BAYONNE, NEW JERSEY, A CORPORATION OF NEW JERSEY

DESIGN FOR A TABLE TOP OR THE LIKE

Application filed September 10, 1932. Serial No. 44,796. Term of patent 3½ years.

To all whom it may concern:

Be it known that I, LEE D. JALKUT, a citizen of the United States, residing at No. 1030 New McNeil Avenue, Nassau County, Lawrence, Long Island, New York, have invented a new, original, and ornamental Design for a Table Top or the like, of which the following is a specification, reference being had to the accompanying drawing, forming part thereof.

Figure 1 is a top plan view of a table top or the like showing my new design.

I claim:

The ornamental design for a table top or the like substantially as shown.

LEE D. JALKUT.
